UNITED STATES PATENT OFFICE.

EDWARD H. McCLOUD, OF COLUMBUS, OHIO.

FLEXIBLE FIRE-RESISTING SHUTTER.

1,013,945.

Specification of Letters Patent.

Patented Jan. 9, 1912.

Application filed January 27, 1908. Serial No. 412,775.

To all whom it may concern:

Be it known that I, EDWARD H. McCLOUD, a citizen of the United States, residing at Columbus, in the county of Franklin and 5 State of Ohio, have invented a certain new and useful Improvement in Flexible Fire-Resisting Shutters, of which the following is a specification.

The object of this invention is to provide 10 an improved construction of slat for the manufacture of flexible shutters or curtains and a shutter or curtain that shall be strong and durable and shall resist fire and shed water.

15 The invention consists in the construction hereinafter described and claimed.

In the accompanying drawings—Figure 1 is a vertical transverse section of a slat according to the invention. Fig. 2 is a side 20 view of the end of several such slats showing end locks.

The slat is indicated as formed out of strips of sheet metal. The outer face of the body 5 of the slat is inclined to the vertical and the upper edge is bent in a horizontal direction as seen at 5^a and formed with a substantially cylindrical roll 5^b. The lower edge of the outer portion of the body of the slat is first bent to form an overhanging lip 5^c and to stand horizontally as seen at 5^d and with a roll 5^f of cylindrical contour but open at its inner side for less than half the circumference or substantially as shown. To complete the tubular body of 35 the slat I secure between the horizontally extending edges of the forward portion of the slat a second strip of sheet metal 8 bent at its upper edge and provided with a roll 8^a fitting within the roll 5^b, and bent at its 40 lower end to extend into and be locked with the metal of the overhanging lip 5^c. In the tubular slat thus formed there can be inserted a strip or core of wood 9 or other material preferably of light weight adapted 45 to retard radiation and conduction of heat.

The body portions referred to are shown to be parallel but the construction in this particular can be modified as can other features within the scope of the invention. 50 Both the horizontal jointing portions project from the same side of the slat and the

slats are joined together by sliding the roll of one lengthwise into that of another, the roll for example 5^b fitting within the roll 5^f. When the slats are thus joined they can 55 freely rock with reference to each other to the extent permitted by the contact of the horizontal portions with the edges of the rolls 5^f. The horizontal portions constitute shoulders taking vertical thrust and because 60 of the considerable extent of their projections they give lateral strength and prevent the ready buckling of the slat and curtain. The end lock (shown more particularly in Fig. 2) is of well known form and comprises a head 6 having an outline that projects beyond the outline of a slat and the joints of the two connected slats so as to form a bearing to prevent wear of the slats by their travel in the channels usually provided for flexible curtains. The end lock 70 also includes a shank 6^a for securing it to the body of the slat, rivets 7 being employed for that purpose. The end locks can be applied to the opposite ends of alternate slats 75 when in the shutter or curtain and they will prevent undue longitudinal movement of the slats on each other.

What I claim and desire to secure by Letters Patent is:

1. A slat for the construction of flexible shutters or curtains consisting of a strip or wall of metal bent to have its edges stand horizontally and formed with rolls, and the face of its body portion having its lower portion formed with a lip to overhang the upper edge of the face of a slat to be joined to it below, combined with a strip or wall of metal in rear of the first mentioned strip or wall bent at its lower edge and connected 85 with said overhanging lip and provided with a roll doubled with the roll at the upper edge of the first mentioned strip to form a single roll, the two rolls thus provided constituting hinging members for connecting the slat with slats having similar hinging members.

2. A slat for the construction of flexible shutters or curtains consisting of a strip or wall of metal bent to have its edges stand 100 horizontally and formed with rolls, and the face of its body portion having its lower

portion formed with a lip to overhang the upper edge of the face of a slat to be joined to it below, combined with a separate strip or wall of metal in rear of the first mentioned strip or wall said last named strip being bent at its lower edge and inserted in said overhanging lip and connected with the

upper edge of the first mentioned strip, substantially as described.

EDWARD H. McCLOUD.
